CLAIM

The ornamental design for a beer bottle and glass, as shown and described.

DESCRIPTION

FIG. 1 is an elevational view showing a side of a beer bottle and glass showing my new design; the opposite side being the same as the side shown;

FIG. 2 is a top plan view of the beer bottle and glass of FIG. 1; and,

FIG. 3 is a bottom plan view of the beer bottle and glass of FIG. 1.

1 Claim, 1 Drawing Sheet

FIG. 1

FIG. 2

FIG. 3
